CROQUET WICKET

Clarence C. Christensen, Muskegon, Mich., assignor, by mesne assignments, to James J. Hamm

Application August 8, 1949, Serial No. 4,361

Term of patent 14 years

(Cl. D34—15)

To all whom it may concern:

Be it known that I, Clarence C. Christensen, a citizen of the United States, residing at Muskegon, in the county of Muskegon and State of Michigan, have invented a new, original, and ornamental Design for Croquet Wicket, of which the following is a specification, reference being had to the accompanying drawing, forming part thereof.

Fig. 1 is a front elevational view of a croquet wicket, showing my new design.

Fig. 2 is an edge view of the same.

The rear elevational view, not shown, of the croquet wicket has the same appearance as the front elevational view shown in Fig. 1.

I claim:

The ornamental design for a croquet wicket, substantially as shown and described.

CLARENCE C. CHRISTENSEN.
